CLAIM

The ornamental design for a bottle with cup, as shown and described.

DESCRIPTION

FIG. 1 is a perspective view of a bottle with cup embodying our new design, shown with the cup in place on the bottle; FIG. 2 is a top view thereof; FIG. 3 is a rear view thereof (the view from the front being the same); FIG. 4 is a side elevational view from the right side of the bottle as shown in FIG. 1 (the view from the left side being the same); FIG. 5 is a perspective view of the bottle shown with the cup removed; FIG. 6 is a top view of the bottle shown in FIG. 5; FIG. 7 is a rear view of the bottle shown in FIG. 5; FIG. 8 is a side elevational view from the right side of the bottle as shown in FIG. 5 (the view from the left side being the same);

FIG. 9 is a perspective view of the bottle shown with the cup removed and the cap on the bottle in an open position; FIG. 10 is a top view of the bottle shown in FIG. 9; FIG. 11 is a rear view of the bottle shown in FIG. 9; and, FIG. 12 is a side elevational view from the right side of the bottle as shown in FIG. 9 (the view from the left side being the same).
